(57) **CLAIM**

The ornamental design for an access door for a bus, as shown and described.

DESCRIPTION

FIG. 1 is a top, front, and left side perspective view of an access door showing our design, as installed on a passenger bus;

FIG. 2 is a top, front, and left side perspective view thereof;

FIG. 3 is a rear perspective view thereof;

FIG. 4 is a front elevation view thereof;

FIG. 5 is a side elevation view thereof;

FIG. 6 is a top plan view thereof;

FIG. 7 is a top, front, and left side perspective view of an access door showing a second embodiment of our new design;

FIG. 8 is a rear perspective view of FIG. 7;

FIG. 9 is a top plan view of FIG. 7;

FIG. 10 is a side elevation view of FIG. 7; and,

FIG. 11 is a front elevation view of FIG. 7.

The environmental structures shown in broken lines throughout the drawings are for illustrative purposes only and form no part of the claimed design.
